UNITED STATES PATENT OFFICE

147,727

DESIGN FOR A COMBINED MAIL CHUTE, SIGNAL CHIME, AND HOUSE NUMBER HOUSING

Lloyd G. Hallamore, Los Angeles, Calif.

Application June 17, 1946, Serial No. 130,770

Term of patent 14 years

(Cl. D74—9)

To all whom it may concern:

Be it known that I, Lloyd G. Hallamore, a citizen of the United States, residing at Los Angeles, in the county of Los Angeles, State of California, have invented a new, original, and ornamental Design for a Combined Mail Chute, Signal Chime, and House Number Housing, of which the following is a specification, reference being had to the accompanying drawing, forming part thereof.

Fig. 1 is a front elevational perspective view of the combined mail chute, signal chime, and house number housing showing my new design.

Fig. 2 is a rear perspective view thereof.

I claim:

The ornamental design for a combined mail chute, signal chime, and house number housing, substantially as shown.

LLOYD G. HALLAMORE.
